GEAR SHIFT KNOB

John R. Henry, 28 Westminster Drive, Oakland, Calif.

Filed May 13, 1965, Ser. No. 85,265

Term of patent 14 years

(Cl. D14—6)

FIGURE 1 is a side elevational view of a gear shift knob showing my new design, with the portions of a lever being shown in broken lines for illustrative purposes only;

FIGURE 2 is a front elevational view thereof;

FIGURE 3 is a top plan view of FIGURE 1; and

FIGURE 4 is a rear elevation view thereof.

I claim:

The ornamental design for a gear shift knob, substantially as shown and described.
